Assistant Examiner — Maheen Khurshid

(57) CLAIM

The ornamental design for a Christmas light, as shown and described.

DESCRIPTION

FIG. 1 is a perspective view of a Christmas light design showing my new design.

FIG. 2 is a front view of a Christmas light.

FIG. 3 is a rear view of a Christmas light.

FIG. 4 is a right side view of a Christmas light;

FIG. 5 is a left side view of a Christmas light.

FIG. 6 is bottom view of a Christmas light.

FIG. 7 is a top view of a Christmas light; and,

FIG. 8 is a perspective view thereof, showing the Christmas light in a state of use.

The broken lines illustrating a string of Christmas lights in FIG. 8 depict environment and form no part of the claimed design.

1 Claim, 8 Drawing Sheets
